Asahel Mungen of Oberlin, State of Ohio.

Letters Patent.

The schedule referred to in these Letters Patent and making part of the same containing a description in the words of the said Asahel Mungen himself of his improvement in the Mathematical instrument called a pendulum Level.

To all to whom these presents shall come,

Be it known that I, Asahel Mungen, of Oberlin in the County of Lorain and State of Ohio, have invented a new and useful improvement in the Mathematical instrument called a Level, and the following is a full and exact description of the construction and operation of said instrument as invented or improved by me.

This improvement consists principally and especially in attaching a tube or a straight bar with a light at each end to the top of a pendulum in such a manner as to admit of being arranged or adjusted (either by screws or otherwise) at right angles with the pendulum and may be suspended within an enclosure of any kind, which shall protect it from the influence of currents of air so that when sustained by a tripod or any convenient stand, the pendulum having a free vibration within its enclosure, coming to rest by the power of its own gravity brings the light to a perfect level.

The particular mode of suspending the pendulum being unimportant, needs no description. That part of the improvement which is claimed to be new and useful, inseparable and essential, and for which particularly Letters Patent are desired, consists in the union of the horizontal tube, or bar, with the pendulum forming thereby a single instrument. But it is contemplated using the same in connection with the compass and quadrant, also it is contemplated making the level of various materials, sizes & proportions that part of the subject is left to the claim and fancy of the manufacturer.

Witness (Signed) Asahel Mungen,
Milroy 25. Mr Johnson (Drawing) (Drawing)
